UNITED STATES PATENT OFFICE.

JOHN JAY HANNAHS, OF NEW YORK, AND ANTHONY A. HIEBER, OF BROOKLYN, NEW YORK, ASSIGNORS TO UNIVERSAL TYPEWRITER COMPANY, A CORPORATION OF NEW YORK.

TYPE-WRITING MACHINE.

No. 849,128.

Specification of Letters Patent.

Patented April 2, 1907.

Original application filed February 4, 1901, Serial No. 45,810. Divided and this application filed October 12, 1905. Serial No. 282,493.

To all whom it may concern:

Be it known that we, JOHN JAY HANNAHS and ANTHONY A. HIEBER, citizens of the United States, residing at the city of New York, in the boroughs of Manhattan and Brooklyn, respectively, and State of New York, have invented certain new and useful Improvements in Type-Writing Machines, of which the following is a full, clear, and exact description.

The present invention relates to that class of type-writing machines in which an open base-frame is supported upon or over the paper to be inscribed and the type-bars, which are actuated by the keys, strike downward through the frame upon the paper. The type mechanism of this class is shown in our application, Serial No. 45,810, filed February 4, 1901, in connection with a flat platen, such as is used for writing upon leaves of books or large sheets of paper.

The chief object of the present invention is to adapt the same type mechanism for use with a movable carriage carrying line-feed rollers. In such new construction the type mechanism is held stationary and the carriage travels longitudinally beneath the same to effect letter-spacing, while the feeding devices upon the carriage serve to shift the paper for line-spacing.

In the present invention the bed of the machine is provided with a hinge-bar to which the type mechanism is attached to be turned upward, if desired, also with track-rails to support the paper-carriage below the type mechanism, and the carriage has upon the top a track-rail which supports the front side of the type mechanism by means of a roll resting thereon.

The present divisional application relates to the construction of the carriage mechanism and particularly the apparatus for feeding and line-spacing the paper thereon.

In the present invention any suitable bed may be used to support the type mechanism above the paper-carriage and any species of rails or guides may be used to support such carriage for longitudinal movement.

In the drawings a machine is represented with a substantially flat bed provided with track-rails to support the paper-carriage by means of rolls upon the carriage and the

type mechanism is sustained above the carriage by the connection of its base-frame with a hinge-bar at the rear side of the bed and by a roller upon the base-frame resting upon a rail provided for the purpose on the carriage.

The construction shown in the drawings will first be described, and any desirable modifications will then be pointed out.

Figure 1 is a transverse sectional view through the carriage and other operative parts of the machine, showing the radiating row of type-bars on one side of the machine. Fig. 2 is a top plan view of the carriage. Fig. 3 is a detail side view of the same. Fig. 4 is a similar view looking from the opposite side of the machine. Fig. 5 is a detail view showing the gears forming part of the paper-feeding mechanism. Figs. 6 and 7 show other details of the carriage relating to the letter-feeding thereof, and Fig. 8 is a detail view showing a portion of the paper-feeding mechanism by which the same serves to line-space the paper.

A designates the bed of the entire machine, having at its rear corners bearings B, projected upwardly to carry the hinge-bar C.

D designates the base-frame of the type mechanism, having type-bars E with heads E', carrying multiple type-faces arranged in rows radiating from opposite sides of the printing-point, as described in our application, Serial No. 45,810.

The finger-keys F are adapted to throw the type-bars downward and print the impressions upon paper beneath the base-frame D in the center of the type-guide a in Fig. 1. Upon the bed A track-rails G G' are fixed, and the paper-carriage has side bars H H', provided, respectively, with flanged and plain wheels I I' to run upon such track-rails. The carriage has end bars J, supporting at their front ends a rail c, to support a roll b, pivoted upon the front of the base-frame D. The rear edge of the base-frame has lugs C', secured upon the hinge-bar C, and such lugs and the roll b support the type mechanism in its operative position above the paper-carriage, which is free to move longitudinally upon the track-rails G G'.

A revoluble polygonal platen K is journaled in the carriage along the middle line

thereof and is provided at one end with a knob K', whereby it may be rotated. The usual notched wheel K² is fixed to the platen, and a detent (not shown) of any usual construction co-operates with said wheel to prevent accidental revolution of the platen. Feeding-rolls L are journaled upon the carriage-bars J at opposite edges of such platen, and a rack-bar M to feed the carriage for letter-spacing is carried upon the rear edge of the carriage by pivoted arms m, (see Figs. 2, 3, 4,) depressible by lever Q. Leaf-springs d are extended from the rack-bar M and the rail e toward the tops of the feeding-rolls, and pressure-rolls e are journaled upon the ends of such springs, so as to turn when the feeding-rolls are rotated.

Flat plates f and f' are fixed in the carriage at the outer sides of the rolls L, one of them to guide the paper g into the feeding-rolls and the other to lead the paper therefrom, as indicated by the dotted line g' in Fig. 1. At the right-hand end of the paper-carriage, the inside of which is shown in Fig. 25, the feeding-rolls are connected by gears l and l' with a central gear l', having attached to its hub (on the outer side of the carriage-bar J) a ratchet-wheel h, and a line-feed lever N is pivoted upon the same end of the carriage and connected with an arm n, carrying a pawl n' to engage the ratchet-wheel h.

A spring N' presses the arm and the pawl normally downward as far as permitted by an adjustable stop i, which is journaled upon the axle of the ratchet-wheel h, and may be set in different positions around said wheel by a spring-stud j, fitted to any one of a series of holes k in the frame-bar J. A spring n² is provided to press the pawl n' normally into the wheel h; but the lower end of the pawl is formed with a shoulder which when it contacts with the stop i (see Figs. 3 and 8) throws it out of the teeth upon said wheel, so that the feeding-rolls may be rotated manually by a knob h'. (Shown in Fig. 2.)

The rack-bar is engaged by the usual feed-pinion m', Figs 1, 6, and 8, which is provided with the usual escapement-wheel m², having connections p to the spacing-key F' and the

usual connections to the type-keys to space the letters when printed.

What we claim is—

1. In a type-writing machine, a bed having a hinge-bar, a type mechanism supported by said hinge-bar, and arranged to strike downward toward the printing-point, a carriage movable on said bed, a platen journaled in said carriage, a pair of feeding-rolls adjacent to said platen and having their top surfaces in horizontal alinement with the upper surface of said platen, and gear connections between said platen and feeding-rolls.

2. In a type-writing machine, a bed having a hinge-bar, a type mechanism supported by said bar, a carriage movable on said bed, a platen journaled in the carriage and having a plurality of plane faces in the path of said type mechanism, feeding-rolls adjacent to said platen and having their top surfaces in horizontal alinement therewith, and spring-impelled presser-rolls bearing upon said feed-rolls.

3. In a type-writing machine, a bed having a hinge-bar, a type mechanism supported by said hinge-bar, a carriage movable on said bed, a platen journaled in the carriage and in the path of said type mechanism, said platen having a ratchet-wheel thereon, a segment-gear carrying a pawl adapted to move said ratchet-wheel, and a cam actuated when the type mechanism is tilted about said hinge-bar for releasing said pawl.

4. In a type-writing machine, a pair of horizontally-disposed feed-rolls, pressure-rolls bearing against their upper surfaces, a ratchet-wheel positively geared to said feed-rolls, a pawl-carrying lever having a gear-section, and a spring-pressed lever having a gear-section meshing with said first-named gear-section.

In witness whereof we subscribe our signatures in the presence of two witnesses.
